(57) **CLAIM**

The ornamental design for a container lid as shown and described.

DESCRIPTION

FIG. 1 is a perspective view of a container lid; FIG. 2 is a front view of the container lid of FIG. 1; FIG. 3 is a left-side view of the container lid of FIG. 1; FIG. 4 is a rear view of the container lid of FIG. 1; FIG. 5 is a right-side view of the container lid of FIG. 1; FIG. 6 is a top view of the container lid of FIG. 1; and, FIG. 7 is a bottom view of the container lid of FIG. 1. In the drawings, the broken lines show portions of a container and the container lid that form no part of the claim.
